Primary Examiner — Rhea Shields(74) *Attorney, Agent, or Firm* — The Fedde Law Firm; Kenton Fedde; Nathaniel Fedde(57) **CLAIM**

The ornamental design for a medical console with display, as shown and described.

DESCRIPTION

FIG. 1 is a front upper right perspective view of a medical console with display, showing our new design.

FIG. 2 is a front upper left perspective view thereof.

FIG. 3 is a front lower right perspective view thereof.

FIG. 4 is a rear upper left perspective view thereof.

FIG. 5 is a front elevation view thereof.

FIG. 6 is a left side elevation view thereof.

FIG. 7 is a right side elevation view thereof.

FIG. 8 is a rear elevation view thereof.

FIG. 9 is a front upper left enlarged perspective view taken along a portion of FIG. 2; and,

FIG. 10 is a front lower right enlarged perspective view taken along a portion of FIG. 3.

In the drawings, the stippling shows contour and not surface ornamentation.

In the drawings, the broken lines are for the purpose of illustrating environment only and form no part of the claimed design.
